UNITED STATES PATENT OFFICE.

JAMES FRANKLIN ALLISON, OF CHICAGO, ILLINOIS.

HAT APPLIANCE.

1,306,989.

Specification of Letters Patent. Patented June 17, 1919.

Application filed August 17, 1918. Serial No. 250,354.

To all whom it may concern:

Be it known that I, JAMES FRANKLIN ALLISON, a citizen of the United States, residing at Chicago, in the county of Cook and State of Illinois, have invented certain new and useful Improvements in Hat Appliances, of which the following is a specification.

This invention has to do with an appliance or attachment for hats, the primary purpose being to more securely hold the hat in position upon the head. In the attainment of this object I have also sought to so construct the present appliance that it will be inexpensive to produce, light in weight, and invisible when in service.

Other objects and uses will also herein-after appear from the following description, wherein reference is made to the accompanying drawing, which exhibits a preferred embodiment of my invention—

Figure 1 being a cross section through a conventional straw hat showing in elevation the present device applied in place; and Figs. 2, 3, and 4 being a perspective, and back and front elevations thereof, respectively.

In carrying out my invention, I make use of a flexible band A preferably of spring material, the ends of which may be slotted or otherwise perforated as at 5 to permit of a stitching or other attachment, if desired, to the inner band 6 of a hat B. To further prevent slipping of the ends of the flexible band A relative to the inner band 6 of the hat, these ends may be toothed as at 7 in such manner as to engage the inner side of its crown 9, this expedient, however, being entirely optional. The flexible band A when not in use may be coiled around the inside of the crown of the hat, where it will remain because of its own spring action. In service, however, the band is positioned somewhat as shown in Fig. 1, in the form of an arch, the ends of the band lying close to the brim 8 of the hat and preferably between its crown 9 and the inner band 6.

Secured to the band A near each end thereof is a plate C whose upper edge 10 is curled inwardly, as best shown in Fig. 1, the bottom edge of this plate having a slight inward curl also, as at 11, and a bent portion 12 extending in the direction of the brim edge. Each plate is secured to the

band A by any convenient means such as a clamp D which is preferably located near the upper edge of the plate, the band lying rearwardly thereof. As seen in Fig. 1, the plate is arranged to lie in front of the inner band 6, while the proximate end of the band A is concealed therebehind, the clamp D being positioned close to the upper edge thereof.

Now it is possible to construct these plates C either flat as shown on one side of Fig. 1, or to give these plates a curvature as shown on the opposite side of Fig. 1. This showing of two formations in the same figure, it will be understood, is solely for purposes of illustration, and would not ordinarily be followed in practice. Normally, the lower portion of each plate is slightly extended toward the center of the hat away from the inner band 6, this being accomplished by the manner of its engagement with the band A, so that when the hat is worn the lower portion of each plate may yield slightly as required to make a comfortable and secure fit upon the head. The upper edges 10 which are curled in a manner to yield easily, are also arranged to engage the head so as to hold the hat immovably in place.

From the foregoing description it will be apparent that the present appliance is not limited in its use to any particular style or kind of hat. In the case of ladies' head-gear, for instance, it will be found very advantageous to employ such a device in place of the unwieldy and unsatisfactory hat pin. In use, moreover, its presence will be entirely concealed, and it may be easily removed from operative position and coiled around within the crown of the hat, where it will remain without further attention. Also, owing to the flexible spring character of the band A, which normally tends to lie flat, the present device will readily adjust itself to hats of different sizes and shapes. For the same reason the device may be easily removed and applied to other hats without the expenditure of any appreciable time or effort. When put to use, the hat may be safely worn at any convenient angle, owing to the pressure exerted along two different points by each plate C which need be only slight for the accomplishment of its intended purpose.

I claim:

1. A hat appliance consisting of a band of spring material adapted to lie within the hat crown in the form of an arch with the ends of the band adjacent the brim of the hat, and a plate associated with each band end in position to engage the head, each plate having upper and lower portions yieldingly arranged for contact with the head, as 5 and for the purpose specified.
2. A hat appliance consisting of a band of spring material adapted to lie within the hat crown in the form of an arch with the ends of the band adjacent the brim of the hat and behind its inner band, means for 10 preventing the band ends from moving within the hat, and a plate secured to each band end and arranged to lie in front of the inner band, the plates being formed in a
- 15

manner to present to the head two lines of 20 contact, yielding in nature, whereby the hat is securely held in place, substantially as described.

3. A hat appliance consisting of two plates arranged to occupy positions on opposite 25 sides of the hat within its crown, and to yieldingly engage the head, a spring band bent to arch shape extending between the two plates in position to not engage the head, means of connection between each plate 30 and the band, and a frictional connection between the band and the hat, whereby the appliance remains secured to the hat, substantially as described.

JAMES FRANKLIN ALLISON.
